UNITED STATES PATENT OFFICE.

ALMA WOODWARD, OF NEW YORK, N. Y.

DESIGN FOR A GARTER OR ARMLET.

Application filed September 15, 1923. Serial No. 7,207. Term of patent 7 years.

To all whom it may concern:

Be it known that I, ALMA WOODWARD, a citizen of the United States, residing in New York city, New York, have invented a new, original, and ornamental Design for Garters or Armlets, of which the following is a specification, reference being had to the accompanying drawing, forming part thereof.

The figure is a plan view of a garter or armlet showing my new design.

I claim:

The ornamental design for a garter or armlet as shown.

ALMA WOODWARD.
